CLAIM

The ornamental design for a speakerphone console, as shown and described.

DESCRIPTION

FIG. 1 shows a top isometric view of a speakerphone console embodying our new design;

FIG. 2 shows a bottom isometric view of the device shown in FIG. 1;

FIG. 3 shows a front elevation view of the device shown in FIG. 1;

FIG. 4 shows a rear elevation view of the device shown in FIG. 1;

FIG. 5 shows a left side elevation view of the device shown in FIG. 1;

FIG. 6 shows a right side elevation view of the device shown in FIG. 1;

FIG. 7 shows a top plan view of the device shown in FIG. 1; and,

FIG. 8 shows a bottom plan view of the device shown in FIG. 1.

(Continued)

The broken lines in the drawings depict parts of the speakerphone console, including the grill, that form no part of the claim.

1 Claim, 8 Drawing Sheets

Related U.S. Application Data

continuation of application No. 29/712,003, filed on Nov. 5, 2019, now Pat. No. Des. 937,237.
